UNITED STATES PATENT OFFICE

FRANK WOLF, OF NEW YORK, N. Y.

HOLDER FOR COLLAPSIBLE TUBES

Application filed January 18, 1928. Serial No. 247,502.

This invention relates to improvements in supporting stands for collapsible tubes, and refers more particularly to such devices wherein the collapsible tubes will be interchangeably held in a substantially upright position.

An important object of the invention in its broader aspects is to provide such a tube holding device with simplified means for effecting clamping engagement on the tube.

Another object is to provide such a device, wherein the tube is held both at its upper and lower ends in such a manner as to be accessible for manual extrusion of the tube contents.

Another object is to provide such a device with a captive service cover for protecting the contents of the tube when not in use.

With the foregoing and other objects in view, the invention resides in the novel features of construction, combination and arrangement of parts hereinafter set forth, shown by way of illustration in the accompanying drawings, and specifically pointed out in the appended claims.

In the drawings, wherein similar reference characters designate corresponding parts throughout the several views—

Figure 1 is a front elevation of an improved tube holder embodying the invention,

Fig. 2 is a side elevation thereof,

Fig. 3 is a front elevation with the parts in adjusted position to facilitate insertion or removal of a tube,

Fig. 4 is a top plan view of the device with the parts in the relative positions shown in Fig. 1,

Fig. 5 is a vertical transverse sectional view on line 5—5 of Fig. 2, and

Fig. 6 is a fragmentary vertical sectional view on a larger scale taken on line 6—6 of Fig. 4.

The illustrated embodiment of the invention is in the nature of a portable stand, comprising a pair of spaced leg members 10 and 11 which are adapted to be disposed longitudinally at opposite sides of the collapsible tube 12. Said leg members may conveniently be formed of sheet metal of considerably less width than the thickness of the tube body and

having outwardly flared portions 13 adjacent their lower ends to provide a suitable supporting base. At their upper ends, said leg members 10 and 11 are secured to or integral with a head member 13 which is annular in form and has a depending peripheral flange 14 adapted to encircle the upper end of the tube 12. Said head member is further characterized by a frusto-conical lower surface 15, against which the upper end wall 16 of the tube is adapted to be seated, and a substantially central aperture 17 is provided in said head member for the reception of the threaded neck 18 of the tube 12, as best shown in Fig. 5.

The leg members 10 and 11 are preferably resilient to the extent that they may be relatively moved toward and away from each other, and they are provided with aligned apertures 19 and 20, through which the end portions of the base strip 21 of the tube are adapted to extend, as shown in Figure 1. The apertures 19 and 20 are preferably rectangular in outline, and of such proportions as to snugly engage the tube base strip 21, whereby to firmly hold the same against lateral displacement within the holder. In order to maintain said leg members in their tube engaging position, a retaining means such as spring clip 22 is pivoted at 23 to the lower end of the leg member 11 and extends transversely to the other leg member 10, with which its curved end 24 is adapted to interlock.

Suitable means are provided for frictionally engaging the outer sides of the tube 12 and maintaining its upper end wall 16 in the frusto-conical seat 15. For this purpose, a yoke member 25 is pivoted at 26 at one side of the head 13; said yoke having curved extremities 27 and 28, which are adapted to be disposed between the outer sides of the tube 12 and the inner side of the peripheral flange 14 and to effect an interlock with the tube by pressing the engaged portions of the tube wall inwardly as at 29 in Figure 6. An outwardly and downwardly extending handle 30 is preferably integral with the yoke 25 to facilitate manipulation of said yoke, and preferably, a pair of spring clips 31 and 32

are carried by the flange 14 in such a manner as to retain the curved ends 27 and 28 in the tube clamping position. It will be evident from the drawings, that as the yoke 25 is 5 swung from its unlocking position, shown in Figure 3 to the locking position, shown in Figure 1, that it will positively force the tube 12 longitudinally to its proper seat within the head 13, and this feature in combination with the engagement of the legs 10 and 11 against the base 21, insures the firm support 10 of the tube.

Preferably, a service cover 33 is associated 15 with the head 13, that shown in the drawings being pivoted at 34 and having a projection 35 which is adapted to be engaged by a detent 36 to hold the same in closed position. Said service cover 33 overlies the central aperture 17 in the head 13 in such a manner 20 as to protect the contents of the tube when the same is not in use and doing away with the necessity for the bothersome screw threaded closure caps with which such tubes are provided by their manufacturers.

25 In order to position a tube within the novel stand, the parts are first related, as shown in Figure 3, whereupon the tube 12 can be slipped endwise into the holder. Thereafter, the leg members 10 and 11 are moved inwardly 30 toward each other in such a manner as to embrace the tube base strip 21 and are locked in such a position by the spring 22. The handle 30 is then pressed downwardly to cause the curved arms 27 and 28 to clamp the 35 end portion of the tube body as previously described. The construction of the improved stand is extremely simple, and therefore, adapted for economical production, and furthermore, the device will be extremely attractive in appearance and portable in 40 service.

Obviously, the invention is susceptible of numerous modifications in the details of construction and arrangement of parts, and the 45 right is herein reserved to make such changes as fall within the scope of the appended claims.

Having thus described my invention, what I claim is:—

50 1. In a holder for collapsible tubes, a stand having spaced leg members adapted to straddle a tube, a head member on the upper ends of said leg members, said head member being centrally apertured for the reception of 55 the neck of the tube, and tube clamping means pivoted on said head member.

2. In a holder for collapsible tubes, a stand having spaced leg members adapted to straddle a tube, a head member on the upper 60 ends of said leg members, said head member being centrally apertured for the reception of the neck of the tube, and having a frusto-conical lower surface against which the upper end of the tube is adapted to seat, and 65 adjustable means mounted on said head mem-

ber to engage the tube and clamp the same against said frusto-conical seat.

3. In a holder for collapsible tubes, a stand 70 having spaced leg members adapted to straddle a tube, a head member on the upper ends of said leg members, said head member being centrally apertured for the reception of the neck of the tube, and having a frusto-conical lower surface against which the upper 75 end of the tube is adapted to seat, and clamping means pivoted adjacent one side of said head member to frictionally engage the tube and clamp the same against said frusto-conical seat.

4. In a holder for collapsible tubes, a stand 80 having spaced leg members adapted to straddle a tube, a head member on the upper ends of said leg members, said head member being centrally apertured for the reception of the neck of the tube, and having a frusto-conical lower surface against which the upper 85 end of the tube is adapted to seat, clamping means pivoted adjacent one side of said head member to frictionally engage the tube and clamp the same against said frusto-conical seat, and means for maintaining the leg members in engagement with the lower end 90 of the tube to hold the same against lateral displacement.

5. A holder for collapsible tubes, formed of 95 sheet metal and comprising an annular head member having a central aperture for reception of the neck portion of a tube, a pair of spaced leg members depending from the head portion and adapted to receive the tube between them, said leg members being movable 100 toward and away from each other and having means for engaging the opposite ends of the base of the tube, detachable means for maintaining the lower ends of the leg members in such tube-engaging position, and a tube 105 clamping member pivoted to the head member and having portions for engaging opposite sides of the tube with a gripping action to support the same in the holder.

6. A holder for collapsible tubes, formed 110 of sheet metal and comprising an annular head member having a central aperture for reception of the neck portion of a tube, and being further characterized by a frusto-conical lower side against which the upper end 115 of the tube is adapted to seat, a pair of spaced leg members integral with said head member and resilient whereby to be movable toward and away from each other, said leg members having aligned apertures adjacent their lower ends to engage the opposite ends of the base 120 of the tube, means for locking said lower ends of the leg members in tube engaging position, and tube clamping means mounted on the 125 head member, said clamping means being in the nature of a pivoted yoke adapted to engage the opposite sides of the tube adjacent its outlet end and to deflect wall portions thereof inwardly, whereby to positively main- 130

tain the upper end of the tube against said frusto-conical seat.

7. A holder for collapsible tubes, comprising a head member having a seat to receive the outlet end wall of the tube, a pair of legs attached to the head member between which the body of the tube is disposed when the outlet end wall of the tube engages said seat, said head member being provided with means adapted to press the outlet end wall of the tube to said seat and means for holding the legs to retain the body of the tube in the position in which it is moved when the outlet end wall is pressed into said seat in engaging position.

8. A holder for collapsible tubes, comprising a head member having a seat for receiving the outlet end wall of the tube, a pair of leg members attached to the head member and arranged to self-support the same, a device with clamping arms pivoted on the head member and adapted to be moved on its pivot for forcibly pressing the clamping arms upwardly against the outlet end wall to move the same firmly into said seat in the head member, seats in the leg members for receiving the base portion of the tube to insure the support of the body of the tube, and a clip part for connecting the lower portions of the leg members.

9. A holder for collapsible tubes, comprising a head member having a seat for receiving the outlet end wall of the tube, a pair of resilient leg members attached to the head member and arranged to self-support the same, a device pivoted on the head member and provided with clamping means for clamping against the outlet end wall of the tube, said device being actuatable on its pivot for forcibly pressing its clamping means upwardly against the outlet end wall to move the outlet end wall firmly into its seat in the head member, and a connection for clamping the leg members in position to engage with and support the body of the tube.

10. A holder for collapsible tubes, comprising a head member having a seat for receiving the outlet end wall of the tube, leg supports for the head member arranged to receive the body of the tube therebetween, a device pivoted on the head member and provided with clamping means for clamping against the outlet end wall of the tube, said device being actuatable on its pivot for forcibly pressing its clamping means upwardly against the outlet end wall to move the tube longitudinally upwardly and firmly position the outlet end wall in the seat of the head member, and seats in said leg members for receiving the base portion of the tube, whereby to insure the support of the body of the tube in the position in which it is moved and clamped by said clamping device.

11. A holder for collapsible tubes, comprising a head member having a seat for re-

ceiving the outlet end wall of the tube, a flange depending from said head member, a pair of leg members attached to the head member and arranged to self-support the same, a clamping device pivoted on the head member and provided with arms adapted to work inside said flange, said device being movable on its pivot for forcibly pressing the arms upwardly between said flange and the tube and against said outlet end wall so as to move the outlet end wall firmly into its seat in the head member and maintain it in such position, and means remote from said head member for connecting the leg members to maintain them in a condition of stability.

In testimony that I claim the foregoing as my invention, I have signed my name hereto.

FRANK WOLF.
